UNITED STATES PATENT OFFICE.

ARTHUR C. HAYDEN, OF BROCKTON, MASSACHUSETTS.

MAT.

Application filed November 10, 1921. Serial No. 514,208.

To all whom it may concern:

Be it known that I, ARTHUR C. HAYDEN, a citizen of the United States, residing at Brockton, in the county of Plymouth and State of Massachusetts, have invented an Improvement in Mats, of which the following description, in connection with the accompanying drawings, is a specification, like characters on the drawings representing like parts.

The invention to be hereinafter described relates to mats for doorways, corridors, passageways, and other uses.

A good form of mat for these purposes may comprise laminated blocks or elements of leather or other suitable material, which may be strung on rods or strong wires, desirably with a disposition such that the assembly of blocks or elements presents a checker-work appearance.

In a mat thus constructed, the blocks are in a sense links which may rock on the axes of the rods, and thereby allow the mat to flex to a certain extent, and naturally adapt the same to the surface of the floor or other support therefor.

It is desirable that the mat may be susceptible of further flexion, so that it may more readily adapt itself to the floor or support and remain in flat condition.

A purpose of the present invention, therefore, is to provide a mat which may flex or bend along transverse lines, so that the mat will always lie close to the floor and remain in flat condition; and the margins of the mat will not stand up from the floor and be liable to trip and injure persons approaching the mat.

In carrying this feature of the invention into practical effect, in the present instance, the wires may be formed to present series of links or loops which are articulated or pivotally connected in end-to-end relation. The construction is such that the mat may not only flex along the axes of the legs of the wire links or loops, but also may flex along lines transverse to said axes. The length of the wire links or loops and the number thereof may be varied to furnish as many lines of flexion as desired, but for purposes of illustration, in the present instance, the length and number of the links are such that the mat is susceptible of flexion along two lines spaced substantial distances from opposed edges of the mat.

With the aforesaid and other purposes in

view, the character of the invention may be best understood by reference to the following description of one good form of the invention shown in the accompanying drawing, wherein:

Fig. 1 is a plan of a mat embodying the invention, certain parts being broken away;

Fig. 2 is a vertical section taken on line 2—2 of Fig. 1;

Fig. 3 is a vertical section taken on line 3—3 of Fig. 1;

Fig. 4 is a vertical section taken on line 4—4 of Fig. 1; and

Figs. 5 and 6 are details of a modified form of the invention.

Referring to the drawing, the mat shown therein as one good form of the invention, comprises an assembly of blocks or elements 1 which may be formed of leather or other appropriate material. In the present instance, these blocks have a laminated character, and each comprises four leather pieces 3 which conveniently may be died out of sole leather. It will be understood that the number of these pieces may be varied as desired.

Suitable means may be provided for securing the blocks or elements in assembled relation, so that the mat may flex along transverse lines for the purposes described. This means, in the present instance of the invention, comprises links or loops 5 which may be formed of wire of suitable metal. These rods or wires may be bent into U-shaped form, and the legs 7 thereof may be entered through registering holes in the blocks. Then the terminals 9 of the legs may be turned in toward one another to complete the wire links.

Some of the blocks 11 may be threaded on both legs of the links in spaced relation, and others 13 may be threaded on legs of adjacent links in alternating relation with the blocks 11, and serve as connecting elements therefor. The construction is such that the mat may flex along the axes of the legs of the links. The blocks thus assembled and strung on the wire links, present a checker-work appearance.

Suitable means may be provided pivotally to connect the terminals of the links which are aligned or in end-to-end relation. This means, in the present instance, comprises flattened sleeves 15 which may be conveniently died out of sheet material and wrapped about the terminals of the adjacent links. The meeting edges of each of the

sleeves may be suitably secured together. The construction is such that the links of each line of links are hinged or pivotally connected so that the mat may flex along 5 lines perpendicular or transverse to the axes of the legs of the links.

It is desirable that the hinged sleeves 15 may be spaced somewhat from the blocks adjacent thereto which are threaded on both 10 legs of the links. To accomplish this, in the present instance, thin blocks or elements 17 may be threaded on legs of adjacent links, and these thin blocks may be desirably half the thickness of the other blocks. The construction is such that these thin blocks 17 are arranged in pairs, and the total width of each pair may be substantially equal to 15 the width of one of the blocks 1, and therefore, the thin blocks do not materially destroy 20 the uniform spacing and appearance of the assembly of blocks. The thin blocks 17 may have a spacing such that when a marginal portion of the mat is rocked upward, said blocks will meet and limit the 25 extent of the upward movement thereof.

As stated, the length and number of the wire links may be varied to enable flexion of the mat along as many lines as desired, but in the present instance of the invention 30 for purposes of illustration, each line of links comprises a central long link 19 and shorter marginal links 21, thereby dividing the mat into a central section 23, and marginal sections 25 hinged to the central section along lines 27.

The spaces between blocks at opposite edges of the mat may be filled by small blocks 29 and thinner small blocks 31 which may be threaded on the outer legs of the 40 links at said edges, thereby affording substantially continuous, uninterrupted edges for the mat.

In some instances it may be desirable to provide means for reinforcing these opposed 45 edges of the mat. To accomplish this, in the present instance, the edge blocks 33 may be made somewhat longer than the large blocks, and these blocks 33 and the small blocks 29 and 31 may have registering holes therein 50 receiving rods 35. In order that these rods may not interfere with the flexion of the mat sections, these rods are divided into a central section 37 and marginal sections 39. Washers 41 may be placed at the ends of 55 these rod sections, and the terminals of the latter may be upset to secure the washers thereon.

Sometimes it is desirable to unite several mats disposed in end-to-end relation. To 60 accomplish this, it is merely necessary to remove the rod sections, and to omit the small blocks 29 and 31. Then the long edge blocks 33 of the adjacent mats may be assembled in alternating relation, and the rod 65 sections may be inserted through the regis-

tering holes in these blocks, and thereby connect the mats.

The thickness of the mat is such that ledges or shoulders of substantial depth occur at the edges of the mat margins. Persons approaching these edges are liable to trip against the same. Therefore, it is desirable to provide means to prevent the feet of pedestrians from coming in contact with these shoulders or ledges.

This means may desirably comprise rows or series of inclined tread devices which may be substantially the same as disclosed in my copending application Serial No. 511,799, filed October 31, 1921. Each of these 80 devices may comprise an attaching element which may be conveniently died out of sheet material and present a tongue 43 adapted to be inserted between the end of a link and the block adjacent thereto, said 85 tongue being formed for interlocking engagement with the link.

Projecting from the tongue is a reverse bend 47 carrying a body 49 formed to present hinge lugs 51 at opposite ends thereof. Projecting from the body intermediate the lugs 51 is a stop conveniently in the form of a tab 53 which may be bent downward somewhat from the plane of the body, as will be noted in Fig. 4. The angle of 95 this tab may be varied by bending the same with respect to the body as desired.

A tread member 55 may be conveniently died out of sheet material, and present an inclined tread surface 57 which may be 100 strengthened or stiffened by end wings 59.

Eyes 61 may be formed in these wings, and be adapted to receive the hinge lugs 51 referred to. Preferably these eyes are offset a substantial distance from the upper 105 edge of the tread member, so that the upper marginal portion of the tread surface of said member may overlap the body 49 of the attaching element.

The construction is such that the tread 110 members are so pivotally connected to the attaching elements, that the tread members may rock or gravitate downward on the pivotal lugs 51, so that the lower edges of the tread members will rest upon and be supported by the floor.

These tread members, therefore, will always incline from the floor upward toward and substantially to the level of the upper surface of the mat, so that when a person 120 is approaching the mat, if his foot is not lifted a sufficient height to clear the edge of the mat, it will strike against the inclined tread member or members, and be deflected thereby upward to the surface of the mat. 125 As a consequence, it is impossible for the pedestrian to bring his foot into such contact with the mat as will be liable to cause the marginal portion thereof to bend or curl upward.

It is desirable to provide means to limit downward rocking movement of the inclined tread members, so that when the mat is placed on the floor, they cannot turn inward or under to positions in which they would be inoperative for the purposes described. The stop tabs 53 referred to, lend themselves advantageously for this purpose, and may be adjusted to limit the downward 10 rocking of the tread members as required.

The upward rocking movement of the inclined tread members may also be limited, and this is accomplished, in the present instance, by engagement of the upper marginal portions of the tread members with the bodies of the attaching elements.

The construction of the mat is such that it may flex along transverse lines, and always tend to remain in flat condition on the 20 floor. The marginal sections swing on the hinges connecting the same with the central section, and naturally gravitate down and remain and lie close to the floor. The pivoted inclined tread members at the edges of 25 the margins will also gravitate down, so that their lower edges will always lie in contact with the floor. As a consequence, the margins of the mat can never be caught and bent up by the feet of pedestrians approaching the mat.

In some instances it may be desirable to connect the mat sections by means which may act as a hinge, and also detachably connect the sections.

This means, in the present instance of the invention, comprises hinge clips 63 (Figs. 5 and 6) which may be die cut of resilient sheet material. Each of these clips has a back 65 and flange 67 which may be curved 40 inward and thence outward to present shoulders 69, the construction being such that these clips may be snapped over the ends of adjacent links and permit relative rocking movement of the mat sections.

To facilitate removal of the clips, each may be provided with a pair of upstanding grooves 71 in the back of the clip, the construction being such that a screw driver or other suitable tool may be inserted in one 50 or the other of these grooves to pry the clip upward and thereby cause the flanges 67 to spring past the ends of the links and release the same.

In practice it has been found that it is 55 desirable to limit the length of the links for most satisfactory results, but by these

detachable hinge clips, as many mat sections may be assembled as are required to cover different areas.

It will be understood that the invention 60 is not limited to the specific embodiment shown, and that various deviations may be made therefrom without departing from the spirit and scope of the appended claims.

What is claimed is:—

Claims:

1. A mat comprising sections, each formed of a checker-work assembly of leather blocks disposed in rows, the blocks of adjacent rows being in staggered overlapped relation, and wire loop links having legs threaded through blocks of alternate rows and legs of adjacent links threaded through blocks of rows intermediate the alternate rows; and hinge devices embracing 75 the ends of the links at the juncture of the sections and admitting flexion of the mat along the lines of juncture of the sections and transversely to the lengths of the legs of the links.

2. A mat comprising sections, each formed of an assembly of leather blocks disposed in rows, the blocks of adjacent rows being in staggered overlapped relation, and wire loop links having legs threaded 85 through the blocks and holding the overlapped blocks closely against one another; and hinge means connecting the adjacent ends of the links of the adjoining sections, thereby permitting the sections to flex along 90 the axial lines of the hinge means.

3. A mat comprising sections, each formed of a checkerwork assembly of leather blocks disposed in rows, the blocks of adjacent rows being in staggered overlapped relation, and wire loop links threaded 95 through the blocks and arranged in rows, the blocks adjacent ends of the links being relatively thin as compared to the other blocks on the links; and hinge devices connecting the adjacent ends of the links of the adjoining sections.

4. A mat comprising sections, each comprising rows of leather blocks, and wire loop links threaded through the blocks; and 105 hinge means detachable connecting the ends of the adjacent links of the adjoining sections.

In testimony whereof, I have signed my name to this specification.

ARTHUR C. HAYDEN.
